(**) Term: **14 Years**

(57) **CLAIM**

(21) Appl. No.: **29/175,101**

The ornamental design for a tape recorder with a tuner and a digital audio disc player, as shown and described.

(22) Filed: **Jan. 30, 2003**

DESCRIPTION

(51) LOC (7) Cl. **14-01**

FIG. 1 is a perspective view of a tape recorder with a tuner and a digital audio disc player showing our new design;

(52) U.S. Cl. **D14/168**

FIG. 2 is a front view thereof;

(58) Field of Search **D14/135-136,**

FIG. 3 is a right side view thereof;

D14/156-157, 167-168, 188, 193-198,
257-258; 369/75.1, 75.2, 77.1, 77.2; 455/344,
347, 350-351

FIG. 4 is a left side view thereof;

FIG. 5 is a top view thereof;

FIG. 6 is a bottom view thereof; and,

FIG. 7 is a rear view thereof.
